UNITED STATES PATENT OFFICE.

JOHN H. MUNSON, OF LAKE PARK, MINNESOTA.

AUTOMATIC BELT GUIDE AND THROWER.

1,034,279.

Specification of Letters Patent. Patented July 30, 1912.

Application filed March 13, 1911. Serial No. 613,993.

To all whom it may concern:

Be it known that I, JOHN H. MUNSON, a citizen of the United States, residing at Lake Park, in the county of Becker and 5 State of Minnesota, have invented certain new and useful Improvements in Automatic Belt Guides and Throwers; and I do hereby declare the following to be a full, clear, and exact description of the invention, such as 10 will enable others skilled in the art to which it appertains to make and use the same.

My invention has for its object to provide an improved belt guide and belt shifting device adapted for general use, but especially 15 adapted for use in connection with traction engines, and to the above ends, the invention consists of the novel devices and combinations of devices hereinafter described and defined in the claims.

20 The invention is illustrated in the accompanying drawings, wherein like characters indicate like parts throughout the several views.

Referring to the drawings, Figure 1 is a 25 view showing the improved device in end elevation applied in working position to a traction engine; Fig. 2 is a view of the improved device in side elevation, on an enlarged scale, with some parts sectioned on 30 the line $x^2 x^2$ of Fig. 1; Fig. 3 is a plan view of the improved device, on an enlarged scale, removed from the traction engine, with some parts broken away and with some parts shown in a dotted line position; Fig. 4 is a 35 detail view, on an enlarged scale, with some parts sectioned on the line $x^4 x^4$ of Fig. 3; and Fig. 5 is a detail view, on an enlarged scale, with some parts sectioned on the line $x^5 x^5$ of Fig. 3.

40 Of the traction engine illustrated for the purpose of showing the improved device applied in working position, the numeral 1 indicates the boiler, and 2 the pulley over which runs a belt 3.

45 Referring to the improved belt guide and belt shifting device, the numeral 4 indicates a skeleton supporting bracket, preferably made up of angle irons and, as shown, is secured to one side of the boiler 1, slightly 50 forward of the pulley 2, by means of a clamping band 5. This clamping band 5 is secured to the brackets 4 and extends from both sides thereof around the boiler 1 and is clamped thereon against sliding movement by any suitable means, such as a draw bolt, (not shown) interposed in the clamp-

ing band 5. If desired, two of these clamping bands may be used in place of the one shown. The bracket 4 is provided with a horizontally projecting stem 6 which is rectangular in cross section, except at its extreme outer end portion, which is round and has been indicated by the numeral 7. Loosely telescoped onto the stem 6 is a sleeve 8 that is also rectangular in cross section but considerably larger than the stem 6. This sleeve 8 is slidably mounted on the stem 6, by means of rollers 9 placed within the sleeve 8 and rotatively mounted on nutted bolts 10 passed through the sleeve 8 and arranged in horizontally and vertically extended pairs, at both ends of the sleeve 8. Rigidly secured to and depending from the under side of the sleeve 8 is a stem 11 on which is rotatively mounted a vertically extended guiding and shifting roller 12. At the extreme lower end of the stem 11, a nut has screw threaded engagement therewith and holds the roller 12 in position on the stem 11.

55 Mounted on the stem portion 7 is a pair of collars 13 and 14 having on their opposite inner faces coöperating half clutches 15 and 16, respectively. The collar 14 is provided with a stem 17 which normally extends vertically downward therefrom. On this stem 17 is rotatively mounted a second belt guiding roller 18 that is held on the stem 14 by means of a nut having screw-threaded engagement with the lower end thereof. Normally, the lower section of the belt 3 loosely runs between the laterally spaced and depending rollers 12 and 18. Extending over and between the rollers 12 and 18 is a horizontally extended sleeve-like roller 19 rotatively mounted on a long rod 20 which extends parallel to the stem 6 and stem portion 7 and is supported therefrom at its ends by means of a pair of brackets 21, one of which is secured to the stem 6 and the other thereof is secured to the stem portion 7. This roller 19 keeps the belt 3 out of engagement with the stem 6 and the adjacent parts carried thereby, and thereby prevents undue friction and damage to the belt 3. To prevent binding of the sleeve 8 on the stem 6, when the running belt 3 comes in contact with the roller 12, a bracket 22 is rigidly secured to the under side of the sleeve 8 and projects laterally therefrom. The outer end, 110 of this bracket 22 is bifurcated and the prongs thereof embrace the roller 19 and

have rotatively secured therebetween a roller 23 adapted to run upon the outer surface of the roller 19 as the sleeve 8 travels on the stem 6. The collar 14 is rotatively mounted on the stem portion 7 and the collar 13 is mounted on the stem portion 17 for limited sliding movement and is held against rotation by means of a key mounted in the stem portion 7. As is evident, by sliding the collar 13 on the stem portion 7, the half-clutch 15 is moved into and out of engagement with the half-clutch 16, and when the clutch members are engaged, the belt guiding roller 17 is locked in its depending or operative position.

For sliding the collar 13 on the stem 7, a short lever 24 is provided. This lever 24 is provided at its intermediate portion with a hub which is loosely telescoped onto the stem portion 7 and is pivotally secured thereto by means of a pivot pin 25. The lever 24 is connected to the collar 13 by means of a pair of links 26 pivotally secured to one end of the lever and to opposite sides of the collar 13. The opposite end of the lever 24 to which the links 26 are secured, is bifurcated and between the prongs thereof, is pivotally mounted an anti-friction roller 27, the purpose of which will presently appear. Secured to one side of the sleeve 8 is a forwardly extended spring lever 28 provided at its forward end with a cam surface 29 and a roller engaging seat 30.

When the roller 27 of the lever 24 is engaged by the seat 30 of the lever 28, the half-clutches 15 and 16 are held interlocked and the belt guiding rollers 12 and 18 are in their operative positions. During the outward movement of the sleeve 8, the cam surface 29 engages the roller 27 and moves the lever 24 on its pivot 25, and, through the links 26, separate the half-clutches 15 and 16 and under the return movement of the sleeve 8, the cam surface 29 again returns the half-clutches 15 and 16 to their interlocked position.

The sleeve 8 is moved back and forth on the stem 6 by means of a pair of oppositely projecting cables 31 and 32. The cable 31 which gives the forward movement to the sleeve 8, is secured at one of its ends to a forwardly extended portion of the sleeve 8 and is passed over a guide sheave 33 mounted in an L-shape bracket 34, rigidly secured to the extreme outer end of the stem portion 7. The other end of the cable 31 extends rearward and is secured to a winding drum 35 which, in turn, is rigidly secured near the inner end of a long operating shaft 36 which extends along the side of the boiler 1 and is provided at its outer end with a hand wheel 37 which is within easy reach of the engine platform. The shaft 36 is rotatively mounted in a pair of bearings 38 and 39. The bearing 38 is secured to and carried by the

bracket 4, and the bearing 39 is secured to the rear end portion of the boiler 1. To lock the shaft 36 in set position, a pawl and ratchet device 40 is secured to the shaft 36 and the bearing 39. The cable 32, which gives the return movement to the sleeve 8, is secured at its forward end to a rearwardly projecting portion of the lever 28 and its other end is secured to the winding drum 35. The cables 31 and 32 are so arranged that when one of the cables is wound onto the winding drum 35, the other is unwound therefrom, and vice versa.

The operation of the above described device may be briefly stated as follows: When it is desired to throw the belt 3 off from the pulley 2, the shaft 36 is rotated by means of the hand wheel 37, in a direction to wind the cable 31 onto the drum 35, thereby moving the sleeve 8 outward on the stem 6, thus bringing the roller 12 into engagement with the inner edge of the belt 3. During this same movement, the cam surface 29 acting on the roller 27 of the lever 24, releases the clutch members 15 and 16 at which time the roller 18 is free for swinging movement. As the belt 3 is crowded outward by means of the roller 12 acting on its inner edge, the outer edge of the belt 3 comes in contact with the roller 18 and under the running movement of the belt 3, which is moving in the direction of the arrow marked on Fig. 1, the roller 15 will be swung into a substantially horizontal position, as indicated by dotted lines in Fig. 3, thereby permitting the belt 3 to move under the roller 15 as the same is forced edgewise off from the fly wheel 2 under the continued lateral movement of the roller 12. As soon as the belt 3 drops off from the pulley 2, the roller 18 returns to its normal position under the action of gravity.

What I claim is:

1. In a belt guiding and shifting device comprising a pair of depending belt guiding devices, one of which is mounted for traveling movement toward and from one edge of the belt, and the other of which is mounted for swinging movement in a plane parallel to the plane of movement of said belt, and means for operating said traveling belt guiding device, said swinging belt guiding device being adapted to be engaged by said belt and to be moved into an inoperative position and arranged to be returned to an operative position by the action of gravity.

2. In a belt guiding and shifting device comprising a pair of depending belt guiding devices, one of which is mounted for traveling movement toward and from one edge of the belt, and the other thereof is mounted for swinging movement in a plane parallel to the plane of movement of said belt, arranged to be moved into an inoperative position when engaged by the belt, and

adapted to be returned to an operative position under the action of gravity, means for operating said traveling belt guiding device, and means carried by said traveling belt guiding device for locking and for releasing said swinging belt guiding device when in an operative position, substantially as described.

3. In a belt guiding and shifting device comprising a pair of depending belt guiding devices, one of which is mounted for traveling movement toward and from one edge of the belt, and the other thereof is mounted for swinging movement, arranged to be moved into an inoperative position when engaged by the belt, and adapted to be returned to an operative position under the action of gravity, means for operating said traveling belt guiding device; and means carried by said traveling belt guiding device for locking and for releasing said swinging belt guiding device when in an operative position, including coöperating clutch members, substantially as described.

25 4. In a belt guiding and shifting device comprising a pair of depending belt guiding devices, one of which is mounted for traveling movement toward and from one edge of the belt, and the other thereof is mounted for swinging movement, arranged to be moved into an inoperative position when engaged by the belt, and adapted to be returned to an operative position under the action of gravity, means for operating said traveling belt guiding device and means carried by said traveling belt guiding device for locking and for releasing said swinging belt guiding device when in an operative position, including coöperating clutch members and a cam equipped lever, substantially as described.

5. In a device of the kind described, the combination with a supporting stem, a sleeve mounted to slide thereon, and means for moving said sleeve, of a pair of collars mounted on said stem and having coöperating clutch members, one of said collars being mounted for rotary movement and the other thereof, for sliding movement, belt guiding rollers carried by said sleeve and said rotary collar, and means for moving said sliding collar for rendering said coöperating clutch members operative and inoperative, substantially as described.

55 6. In a device of the kind described, the combination with a supporting stem, a sleeve mounted to slide thereon, and means for moving said sleeve, of a pair of collars mounted on said stem and having coöperating clutch members, one of said collars being mounted for rotary movement and the other thereof, for sliding movement, belt guiding rollers carried by said sleeve and said rotary collar, and means carried by said sleeve for moving said sliding collar for

rendering said coöperating clutch members operative and inoperative, substantially as described.

7. In a device of the kind described, the combination with a supporting stem, a sleeve mounted to slide thereon, and means for moving said sleeve, of a pair of collars mounted on said stem and having coöperating clutch members, one of said collars being mounted for rotary movement and the other thereof, for sliding movement, belt guiding rollers carried by said sleeve and said rotary collar, a lever mounted on said stem, a link connecting said lever and said rotary collar, and an arm carried by said sleeve and operative on said lever to render said coöperating clutch members operative and inoperative, substantially as described.

8. In a device of the kind described, the combination with a supporting stem, a sleeve mounted to slide thereon, and means for moving said sleeve, of a pair of collars mounted on said stem and having coöperating clutch members, one of said collars being mounted for rotary movement and the other thereof, for sliding movement, belt guiding rollers carried by said sleeve and said rotary collar, a lever mounted on said stem, a link connecting said lever and said rotary collar, and an arm carried by said sleeve and having at its free end a cam surface for operating said lever, substantially as described.

9. In a device of the kind described, the combination with a supporting stem, a sleeve mounted to slide thereon, and means for moving said sleeve, of a pair of collars mounted on said stem and having coöperating clutch members, one of said collars being mounted for rotary movement and the other thereof, for sliding movement, belt guiding roller equipped stems depending from said sleeve and said rotating collar, a lever intermediately pivoted to said supporting stem, a link connecting said lever to said sliding collar, and a spring arm carried by said sleeve and having at its free end a cam surface for operating said lever, substantially as described.

10. In a device of the kind described, the combination with a supporting stem, and a sleeve mounted to slide thereon, of a pair of reversely extended cables secured to said sleeve and arranged to move the same in reverse directions, a pair of collars mounted on said stem and having coöperating clutch members, one of said collars being mounted for rotary movement and the other thereof, for sliding movement, belt guiding roller equipped stems depending from said sleeve and said rotary collar, a lever intermediately pivoted to said supporting stem, a link connecting said lever to said sliding collar, and a spring arm car-

ried by said sleeve and having at its free end a cam surface for operating said lever, substantially as described.

11. In a device of the kind described, the combination with a supporting stem, and a sleeve mounted to slide thereon, of a drum equipped operating shaft, a pair of reversely extended cables secured to said sleeve and arranged to be reversely wound 10 on said drum, a pair of collars mounted on said stem and having coöperating clutch members, one of said collars being mounted for rotary movement and the other thereof, for sliding movement, belt guiding roller

equipped stem depending from said sleeve 15 and said rotary collar, a lever intermediate pivoted to said supporting stem, a link connecting said lever to said sliding collar, and a spring arm carried by said sleeve and having at its free end a cam 20 surface for operating said lever, substantially as described.

In testimony whereof I affix my signature in presence of two witnesses.

JOHN H. MUNSON.
